[57] **CLAIM**

The ornamental design for a grommet, as shown and described herein.

DESCRIPTION

FIG. 1 is a top perspective view of a grommet showing my new design with a pivoting wire access member thereof in a raised position;
FIG. 2 is a top plan view thereof with a pivoting wire access member in a lowered position;
FIG. 3 is a top plan view thereof with a pivoting wire access member in a raised position;
FIG. 4 is a bottom plan view thereof with a pivoting wire access member in a lowered position;
FIG. 5 is a front elevational view thereof with a pivoting wire access member in a lowered position;
FIG. 6 is a front elevational view thereof with a pivoting wire access member in a raised position;
FIG. 7 is a rear elevational view thereof with a pivoting wire access member in a lowered position;
FIG. 8 is a rear elevational view thereof with a pivoting wire access member in a raised position;
FIG. 9 is a right side elevational view thereof with a pivoting wire access member in a lowered position and the left side being a mirror image of FIG. 9; and
FIG. 10 is a right side elevational view thereof with the pivoting wire access member in a raised position and the left view being a mirror image of FIG. 10.
